(57) **CLAIM**

The ornamental design for a foldable workstation and shelving system, as shown and described herein.

DESCRIPTION

This design patent application is related to U.S. patent application Ser. No. 09/827,546 filed Apr. 6, 2001 for Foldable Storage Shelves for Shipping Mail and the Like. FIG. 1 is a front, left, top perspective view of our foldable workstation and shelving system with certain rear brackets or braces shown in phantom as well as a chain and pin structure also shown in phantom;

FIG. 2 is a top view thereof;

FIG. 3 is a bottom view thereof;

FIG. 4 is a right, side view thereof with the left side being a mirror image of the right side;

FIG. 5 is a front view thereof;

FIG. 6 is a front, top, left perspective view of the foldable workstation and shelving system shown in FIG. 1 in a folded configuration;

FIG. 7 is a top view thereof;

FIG. 8 is a bottom view thereof;

FIG. 9 is a right side view thereof with the left side being a mirror image of the right side; and,

FIG. 10 is front plan view thereof.
